UNITED STATES PATENT OFFICE

ALFRED J. REEDY, OF BATTLE CREEK, MICHIGAN, ASSIGNOR TO A-B STOVE COMPANY,
OF BATTLE CREEK, MICHIGAN

GAS BURNER

Application filed March 5, 1929. Serial No. 344,309.

The main object of this invention is to provide a gas burner for cooking stoves which is very compact and at the same time is efficient, the gas being very uniformly distributed throughout the burner.

A further object is to provide a gas burner which is well adapted for use in cooking stoves or ranges having concealed manifolds, that is, manifolds that are set into or covered by the frame, thereby decreasing the burner space.

Objects pertaining to details and economies of my invention will definitely appear from the description to follow. The invention is defined in the claims.

A structure which embodies the features of my invention is clearly illustrated in the accompanying drawing in which:

Fig. 1 is a fragmentary side view of my improved burner partially in vertical section on a line corresponding to line 1-1 of Figs. 2 and 3.

Fig. 2 is a fragmentary plan view partially in horizontal section on line 2-2 of Fig. 1, the position of certain of the burner arms removed by the sectioning being indicated by dotted lines.

Fig. 3 is an enlarged detail on line 3-3 of Figs. 1 and 2.

My improved burner comprises an annular body 1 having an annular passage or chamber 2 therein and radial arms 3 opening to the passage. The jet orifices 4 are arranged in radial series so that they are uniformly distributed about the burner.

The mixing tube 5 is relatively short and is disposed tangentially of the annular body and its Venturi passage 6 opens tangentially into the annular passage of the burner body which constitutes a circular extension or continuation thereof. The inwardly expanding portion of the venturi indicated at 7 merges into the walls of the passage 2. This mixing tube is arranged in a plane below the radial arms and its top wall 8 projects into the passage 2 and also its inner side wall 9. These walls constitute baffles for the overlying burner arms and serve to direct the incoming mixture or gases into the burner passage so that it flows around the same in one direction.

The gas nozzle indicated at 10 is controlled from the valve 11. The air shutter is indicated at 12. This arrangement permits the forming of the burner with a very short projecting Bunsen tube portion as a portion of the mixing tube is within the burner body, and at the same time the gas and air are effectively mixed and very uniformly distributed to the jet orifices or other radial burner tip members 13 in which the jet orifices are formed. The central opening 14 in the burner body permits secondary air to flow therethrough.

The upper portion of the wall of this opening 14 is preferably outwardly flared at 15, the inner jet orifices 4 being in this wall.

I have illustrated and described my improvements in an embodiment which I have found highly practical. I have not attempted to illustrate or describe certain modifications or adaptations which I contemplate as it is believed that this disclosure will enable those skilled in the art to embody or adapt the same as may be desired.

Having thus described my invention what I claim as new and desire to secure by Letters Patent is:

1. A gas burner comprising an annular body portion having an annular passage therein and radial arms opening thereto and provided with radially disposed series of jet orifices extending into said arms, and a relatively short mixing tube disposed tangentially of said annular body portion and opening tangentially to said annular passage therein whereby the passage constitutes a curved continuation of said mixing tube, said mixing tube being disposed in a plane below said arms in underlying relation to one of them, the top and inner side wall of said mixing tube being extended into said passage in said burner body portion to constitute baffles for the adjacent burner arms and to direct the incoming gases into said annular passage.

2. A gas burner comprising an annular body portion having an annular passage therein and radial arms opening thereto and provided with radially disposed series of jet orifices extending into said arms, and a rela-

tively short mixing tube disposed tangentially of said annular body portion and opening tangentially to said annular passage therein whereby the passage constitutes a curved continuation of said mixing tube, said mixing tube being disposed in a plane below said arms in underlying relation to one of them.

3. A gas burner comprising an annular body portion having an annular passage therein and radial arms opening thereto and provided with radially disposed jet orifices extending into said arms, and a Venturi mixing tube opening tangentially to said annular passage whereby the passage constitutes a curved continuation of said mixing tube, the expanding portion of said venturi being merged into the walls of said annular passage.

4. A gas burner comprising a body portion having an annular passage therein and provided with jet orifices in communication with said passage, and a relatively short mixing tube opening tangentially to said annular passage whereby the passage constitutes a continuation of said mixing tube, the top and inner walls of said mixing tube being extended into the passage and constituting baffles for the adjacent jet orifices and directing the incoming gases into said annular passage.

30 In witness whereof I have hereunto set my hand.

ALFRED J. REEDY.
